UNITED STATES PATENT OFFICE.

ALBERT GARSKE, OF REEDSBURG, WISCONSIN.

SPARK ARRESTER AND EXTINGUISHER.

SPECIFICATION forming part of Letters Patent No. 696,960, dated April 8, 1902.

Application filed May 31, 1901. Serial No. 62,501. (No model.)

To all whom it may concern:

Be it known that I, ALBERT GARSKE, a citizen of the United States of America, and a resident of Reedsburg, in the county of Sauk, 5 State of Wisconsin, have invented certain new and useful Improvements in Spark Arresters and Extinguishers, of which the following is a full, clear, and exact description, reference being had therein to the annexed 10 drawings, in which—

Figure 1 is a side elevation of my device, and Fig. 2 a transverse vertical section taken on the line 2 2 of Fig. 1. Fig. 3 is a vertical sectional view of a portion of a boiler and 15 smoke-stack provided with my invention.

The object of this invention is to provide a simple device for arresting and throwing back and deadening the sparks before they leave the smoke-stack.

This invention consists in its preferred 20 form of a clamp *a*, adapted to be clamped to the exhaust-pipe in the smoke-box of a locomotive or a traction-engine boiler and to be vertically adjustable thereon. Bolted or riveted to the upper edge of the clamp are a series 25 of three rods *b*, which are of sufficient length to extend up into the smoke-stack when the device is in place in the smoke-box. Bolted or riveted to the upper ends of these 30 rods is an inverted cone *c*, which is supported centrally within the rods. Around the upper part of this cone *c* and parallel with its base are several rows of nails or brads *f*, the nails in each row alternating with those in the row 35 above them and being inserted from within and projecting at right angles to the outside surface of the cone, the heads of the nails or brads being held down in place by another cone of the same size placed within it and 40 resting against the nail-heads, or, instead of nails, screw-bolts, to be screwed directly into the cone, or other pins or projections may be employed. The rods pass through the vertical draft-tube *d*, which is in form the frustum 45 of a cone and is supported by said rods within the lower end of the smoke-stack and

directly over the exhaust-pipe, so that the exhaust-pipe will discharge up through it. The rods are bolted adjustably to the interior of the tube *d*, so that they and the clamp 50 may be vertically adjusted to bring the conical arrester *c* at the proper point with respect to said central draft-tube, and the device at the top is held centrally in the smoke-stack by means of rods *e*, bolted or riveted 55 to the inside of the cone *c* and extending to and resting against the inside of the smoke-stack.

It will be observed that the sparks are directed against the bradded cone and are 60 thereby thrown back and deadened.

Having thus fully described my invention, what I claim, and desire to obtain by Letters Patent, is—

1. In a spark-arrester, the combination of a 65 series of supporting-rods provided with means at their lower ends for securing them to a support, a draft-tube supported on the rods, and an inverted cone supported above the draft-tube and provided with numerous outward-extending pins.

2. In a spark-arrester for smoke-stacks, the combination of a series of rods provided with means for adjustably securing them to a support at their lower ends, a draft-tube supported on the rods intermediate their ends, an inverted cone attached to the upper ends 75 of the rods above the draft-tube and provided with numerous outward-extending pins, and means for centering the apparatus in the 80 smoke-stack consisting of a series of fingers attached to the inverted cone and extending upward and outward and adapted so as to bear movably against the interior of the stack.

In testimony whereof I hereunto affix my 85 signature, in the presence of two witnesses, this 27th day of May, 1901.

ALBERT GARSKE.

Witnesses:

PATRICK DALY,
J. F. O'BRIEN.
